(57) **CLAIM**

I claim the ornamental design for a pet harness, as shown and described.

DESCRIPTION

FIG. 1 is a downward front perspective view of the claimed design.

FIG. 2 is an upward front perspective view thereof.

FIG. 3 is a top plan view thereof.

FIG. 4 is a bottom plan view thereof.

FIG. 5 is a right-side elevation view thereof.

FIG. 6 is a left-side elevation view thereof.

FIG. 7 is a front elevation view thereof; and,

FIG. 8 is a rear elevation view thereof.

The solid lines represent the bounds of the claimed design, whereas those features shown in broken lines, such as the front control line connector, shown in FIGS. 1,2, and 4-8, the back strap connector, shown in FIGS. 1-3 and 5-7, the control line buckles, shown in FIGS. 1-6 and 8, and the hook-and-loop fasteners, shown in FIGS. 1-3, form no part of the claimed design.
